(57) **CLAIM**

The ornamental design for a refrigerator case door, as shown and described.

DESCRIPTION

FIG. 1 is a top, right, front perspective view of a refrigerator case door;

FIG. 2 is a bottom, left, front perspective view thereof;

FIG. 3 is a front elevation view thereof;

FIG. 4 is a rear elevation view thereof;

FIG. 5 is a left side view thereof;

FIG. 6 is a right side view thereof;

FIG. 7 is a top plan view thereof; and,

FIG. 8 is a bottom plan view thereof.

(Continued)

The different line shading shown in FIGS. 1-8 indicate contrast in surface materials. The oblique shade lines in the FIGS. 1-8 show a transparent, reflective, or shiny surface, and not surface ornamentation.

The broken lines shown in the drawings illustrate portions of the component of the refrigerator case door that form no part of the claimed design.
